UNITED STATES PATENT OFFICE.

JOSEPH DEMYEN, OF PHILADELPHIA, PENNSYLVANIA.

TENSION PAD FOR LET-OFF PULLEYS.

Application filed November 30, 1921. Serial No. 518,764.

To all whom it may concern:

Be it known that I, JOSEPH DEMYEN, a citizen of the United States, residing at Philadelphia, in the county of Philadelphia and State of Pennsylvania, have invented new and useful Improvements in a Tension Pad for Let-Off Pulleys, of which the following is a specification.

My invention relates to a new and useful improvement in a tension pad for warp let off pulleys for looms and the like, and has for its object to provide an exceedingly simple and effective device of this description whereby the ropes or chains on the warp let off pulleys will work smoothly and positively in all kinds of weather thereby providing a smooth positive tension upon the warp let off roll which will materially improve the product of the loom.

20 A further object of my invention is to prevent the waste of the powder now used upon let off pulleys which waste by accumulation upon the floor adjacent the loom becomes a source of annoyance and danger.

25 by reason of making the floor slippery and thus causing frequent accidents.

With these ends in view, this invention consists in the details of construction and combination of elements hereinafter set forth and then specifically designated by the claims.

In order that those skilled in the art to which this invention appertains, may understand how to make and use the same, I will 35 describe its construction in detail, referring by numerals to the accompanying drawings forming a part of this application, in which:

Fig. 1, is a perspective of a portion of a warp let off roll showing a let off pulley on one end thereof and illustrating the operation of my improved pad to said pulley.

Fig. 2, is a perspective of a pad made in accordance with my improvement.

45 Fig. 3, is a section on the line 3—3 of Fig. 2.

Fig. 4, is a perspective of a slightly modified form of my invention.

50 Fig. 5, is a perspective showing the manner of folding the strip of fabric to produce a pad.

In carrying out my invention as here embodied, 1 represents the pad or container which is preferably composed of a loosely woven or porous fabric or any other suitable material folded and refolded to produce a

porous distributor with a backing or cushion 2 and a pocket 3, said pocket being intended for the reception of a suitable anti-friction powder such as powdered soap 60 stone, pumice stone or graphite. The layers of this pad may be stitched together as indicated at 4 or secured together in any other suitable manner.

In producing this pad I prefer to utilize 65 a strip of fabric and first fold the same upon the lengthwise lines 5 producing the flaps 6 as indicated in Fig. 5 and placing the desired quantity of anti-friction powder beneath the flap in the central portion of the strip and then folding the strip crosswise upon the dotted lines 7 so that the ends of the strips become flaps and superimposed upon the body after folding as will be readily understood.

75 By this construction it will be seen that the powder contained within the pocket may be gradually and evenly sifted therefrom for application as hereinbefore explained.

This pad is placed beneath the let off rope 80 or chain 8 and against the face of the let off pulley 9 around which said chain or rope is coiled as clearly shown in Fig. 1 and will thereafter apply a sufficient amount of powder from the pocket of the pad to the 85 surfaces of said pulley to prevent the rope or chain from sticking or taking an undue grip upon said pulley.

In placing this pad beneath the coils of the let off rope said coils may be slightly 90 spaced apart and will maintain this spacing by becoming embedded into the upper surface of the pad which will greatly facilitate the action of the rope or chain upon the pulley and it is to be noted that as the 95 inner surface of the pad which bears upon the pulley is constantly supplied with the anti-friction powder said pad will assist in maintaining an even grip between the rope or chain and pulley.

100 By the use of my improved pad I have found that the product of a loom is increased in quality since the given steady tension is maintained upon the cloth, thus avoiding defects and flaws in the weave which would 105 otherwise take place if this tension were materially varied as is the case in present day practice.

Another incidental but considerable advantage in the use of my improved pad is 110 that the powder which has heretofore been applied directly to the pulley and shed from

said pulley to the floor making the latter slippery from which many accidents have occurred is hereby entirely overcome, since the powder is only applied to the surfaces 5 of the pulley by being held against the same and distributed during the rotations thereof.

In Fig. 4, I have shown a slight modification of my improvement in which a relatively stiff backing 10 is secured to the pad 10 1 in any suitable manner, said backing being of leather, metal or other suitable material.

When the powder within the pocket of the pad has become exhausted the pad is removed and another substituted therefore and if desired the removed pad may be opened and the pocket thereof again filled with powder. This removal and substitution is exceedingly simple requiring no alteration 20 or adjustment of any part of the loom.

While my invention is especially adapted for use upon the warp let off pulleys of looms it is obvious that it may be used to advantage upon let off pulleys or any other 25 type of machine accomplishing the same results as here described, and a container may be made or manufactured in various shapes, forms or types and out of different kinds of material, such as metal, hard rubber, 30 woven wire etc. and which right I desire to reserve to myself.

Of course I do not wish to be limited to the exact details of construction as herein shown as these may be varied within the

limits of the appended claims without departing from the spirit of my invention. 35

Having thus fully described my invention, what I claim as new and useful is:—

1. As a new article of manufacture, a pad for let off pulleys having a pocket 40 therein for containing a suitable powder, the outer wall of said pocket being capable of permitting the gradual passage of said powder.

2. A pad for let off pulleys consisting of 45 a strip of fabric folded longitudinally to form a body and two flaps folded crosswise to produce a pocket, said pocket being filled with an anti-friction powder.

3. In combination with a let off pulley 50 and a rope coiled about said pulley of a powder containing pad interposed between the coils of said rope and the face of said pulley.

4. A pad for let off pulleys comprising a 55 coarsely woven fabric so folded as to produce a pocket and an anti-friction powder contained within said pocket.

5. A pad for interposition between the face of the let off pulley and the rope or 60 chain coiled about the same, comprising a loosely woven fabric so folded as to provide a pocket, anti-friction powder contained within said pocket, and a backer composed of stiffer material than the pad. 65

In testimony whereof, I have hereunto affixed my signature.

JOSEPH DEMYEN.
